UNITED STATES PATENT OFFICE.

THOMAS JEFFERSON SHORT, OF DANVILLE, ILLINOIS.

CLEANER FOR CAR-WINDOWS.

No. 856,428.

Specification of Letters Patent.

Patented June 11, 1907.

Application filed June 16, 1906. Serial No. 322,064.

To all whom it may concern:

Be it known that I, THOMAS JEFFERSON SHORT, a citizen of the United States, residing at Danville, in the county of Vermilion and State of Illinois, have invented a new and useful Cleaner for Car-Windows; and I do hereby declare the following to be a full, clear, and exact description of the invention, such as will enable others skilled in the art to 10 which it appertains to make and use the same.

This invention relates to certain new and useful improvements in car window attachment and the invention consists essentially 15 in providing a device for cleaning both sides of a car window of the steam, rain, snow and ice.

A further object of the invention is to provide means whereby as one lever of the device is rotated, the lever upon the opposite side of the glass will travel in unison therewith.

This invention comprises further objects and combinations of elements which will be 25 hereinafter more fully described and shown in the accompanying drawings, and the novel features thereof will be particularly pointed out by the appended claims.

To obtain a full and correct understanding 30 of the details of construction and combination of features and elements and advantages, reference is to be had to the hereinafter set forth description in connection with the accompanying drawings wherein

35 Figure 1 is a front elevation of a car window showing the invention as applied thereto. Fig. 2 is a sectional view on line 2—2 of Fig. 1. Fig. 3 is a view showing a modified application of the invention. Fig. 4 is a perspective view of the device detached. Fig. 5 is a sectional view on line 5—5 of Fig. 4. Fig. 6 is a detail perspective view of the bushing.

Making renewed reference to the accompanying drawings wherein similar reference 45 characters indicate the corresponding parts in the several illustrations, by figures, 1 designates the glass of a car window to which the improved device is connected by means 50 of a bolt 2, said bolt passing through aper-

tures 3 in the two arms 4 each of which projects from the ends of the metallic lever 5 and also in the same plane therewith.

The parts of the bolt which engage the apertures 3 of the arms are square in cross section or flattened, as at 6, so as to cause the two levers to travel together for the purpose of cleaning both sides of the glass of the window. The part of the bolt which passes through the glass is also square but to obviate the friction of the corners of the square part upon the inner circumference of the aperture 7 in the glass, a suitable bushing 8 is provided, the outer circumference thereof being of cylindrical contour so as to allow the 65 levers to have free and easy movement thereof.

To cause the bushing, when the levers are operated, to rotate with the bolt, it is provided with a square outlined aperture 8^a. 70 To clamp the parts together, a nut 9 is threaded upon said bolt, but the clamping action is just sufficient to allow the levers to operate, without allowing them to bind against the glass.

The levers 5 are formed of any suitable 75 metal and are provided with longitudinal grooves 10, the walls of which are inclined as shown in the drawings. These grooves receive elongated rubber wipers 11 which 80 are provided for the purpose of removing the steam, rain, snow and ice.

The lever upon the inner side of the glass is provided with a knob or hand piece 12 for the purpose of rotating the levers.

From the foregoing, the essential features 85 and elements of the device, together with the simplicity thereof, will be plainly observed, and when manufactured in accordance with the invention, an inexpensive market will be 90 easily obtained therefor.

Having thus fully described the invention, what is claimed as new and useful with the protection of Letters Patent is:—

A window cleaning device, comprising a 95 pair of levers, having wipers, arms each having a square outlined aperture, extending from said levers, a bushing having a square outlined aperture disposed between the arms, said bushing being provided with an outer 100

cylindrical circumference to allow the levers to have free and easy movements, said bushing being disposed in a bearing of the window, a bolt and thumb nut for fastening the parts 5 together, said bolt having a partly square outlined shank to cause the levers and bushing to rotate together.

In testimony whereof I have hereto affixed my signature, in the presence of two witnesses.

THOMAS JEFFERSON SHORT.
